COVERED PIZZA TRAY

Jeno F. Paulucci, Duluth, Minn., assignor to
Jeno's, Inc., Duluth, Minn.

Filed July 2, 1971, Ser. No. 159,575

Term of patent 14 years

Int. Cl. D9—03

U.S. Cl. D9—184

FIG. 1.

FIG. 2.

FIG. 3.

FIG. 4.

FIG. 1 is a top plan view of a covered pizza tray showing my new design, a portion of the cover is fragmentarily shown to reveal the top interior of the tray;

FIG. 2 is a side elevational view of the covered pizza tray;

FIG. 3 is a bottom plan view thereof;

FIG. 4 is an enlarged sectional view taken on line 4-4 of FIG. 1.

I claim:

The ornamental design for a covered pizza tray, as shown and described.
